UNITED STATES PATENT OFFICE.

IRWIN DAVIS, OF KIRKSVILLE, MISSOURI.

KNOCKDOWN CHICKEN-COOP.

1,094,441.

Specification of Letters Patent. Patented Apr. 23, 1912.

Application filed March 23, 1911. Serial No. 616,467.

To all whom it may concern:

Be it known that I, IRWIN DAVIS, a citizen of the United States, residing at Kirksville, in the county of Adair and State of Missouri, have invented certain new and useful Improvements in Knockdown Chicken-Coops; and I do declare the following to be a full, clear, and exact description of the invention, such as will enable others skilled in the art to which it appertains to make and use the same.

This invention is an improved knock down chicken coop and brooder.

One object of the invention is to provide a coop or brooder formed of a plurality of detachably connected sections which may be readily assembled and quickly and easily separated, and the parts nested together in compact form.

Another object is to provide a coop of this character having a raised bottom and a curved or rounded top which will prevent the chickens from roosting thereon and which is provided with an improved construction of door having means whereby the same may be held in closed and partly closed positions and means to support the same in a raised or open position.

With these and other objects in view, the invention consists of certain novel features of construction, combination and arrangement of parts as will be more fully described and particularly pointed out in the appended claims.

In the accompanying drawings: Figure 1 is a perspective view of my improved coop or brooder, set up in position for use; Fig. 2 is a central vertical sectional view showing the door in closed position in full lines and in open position in dotted lines; Fig. 3 is a cross sectional view on the line 3—3 of Fig. 2; Fig. 4 is a rear end view; Fig. 5 is a detail horizontal sectional view through one of the rear corners of the coop on the line 5—5 of Fig. 4; Fig. 6 is a detail inverted perspective view of the bottom of the coop; Fig. 7 is a perspective view of the rear end of the coop; Fig. 8 is a similar view of a portion of the combined top and sides of the coop; Fig. 9 is a detail perspective view of one of the locking members for fastening the bottom and sides of the coop together.

My improved coop or brooder comprises front and rear end pieces 1 and 2, a bottom piece 3 and combined top and sides 4 and 5.

The front and rear end pieces 1 and 2 have their upper edges curved or formed on an arc as shown. On the side edges of said pieces are formed vertical offset guide channels 6. In the center of the curved upper edges of the piece are formed upwardly projecting locking lugs 7 the purpose of which and the guide channels 6 will be hereinafter described. In the lower edge 65 of the rear end piece 2 adjacent to the offset guide channels 6 are formed V-shaped notches 8 the purpose of which will herein-after appear.

In the upper portion of the rear piece 2 are formed a series of ventilating openings 9, said openings being preferably formed by semi-circular slits cut in the rear piece as shown. The part of the metal within the semi-circular slits is struck or bent outwardly to form guards or shields 10 for the openings 9.

In the front end 1 of the box is formed a doorway 11 which is adapted to be closed by a slidably and hingedly mounted door 12 comprising a flat metal plate having its upper end bent to form an elongated loop 13 extending entirely across the width of the door, slidably and hingedly mounted on a track bar 14 having its ends bent inwardly and inserted through apertures in the front of the coop and then bent downwardly and clenched against the inner side of the end as shown. By thus attaching the door it may be moved laterally across the front end of the coop to either end of the track bar thus partly opening the doorway at either side; the lower end of the door engaging in a space between the front 1 and the front flange 22 of the bottom 3. By thus arranging the door it may also be swung upwardly to a full open position as shown in dotted lines in Fig. 2. To open the door to the dotted line position of the Fig. 3, it is first raised until the track bar 100 14 is in the lower part of the bearing loop 13, then the lower end of the door is moved outward beyond the flange of the bottom 3, then dropped and swung outwardly and upwardly, with the track bar in the upper 105 portion of the loop as a pivot, until a vertical position is reached, when the door is dropped into said dotted line position of Fig. 3, in which position the loop in its reversed position will prevent accidental 110 falling or closing of the door and firmly lock it in its open position. When it is de-

size. To close the door, it is again raised to the limit of the loop 13, swung outwardly and downwardly to a position outside the flange of the bottom, raised again above the 5 flange, pressed inward, and dropped behind the flange. The door 12 may be provided with ventilating openings 15, and a suitable handle 16.

The top 4 and sides 5 are formed from a 10 single sheet of metal comprising straight sides and bent or curved top. In the curved upper edge of the front and rear ends of the coop and in said curved top piece are formed transversely disposed grooves 17 15 which are adapted to receive the upper curved edges of the ends 2 and 3 of the coop. In the center of the top piece adjacent to its ends are formed slots 18 with which are engaged the lugs 7 formed on the 20 front and rear ends whereby the upper portions of said ends are secured to the top. The front and rear edges of the metal forming the edge of the top piece 4 are beaded or folded back upon themselves to provide 25 a smooth finish for the ends and to reinforce the same.

On the ends of the side pieces 5 are formed right angular locking flanges 19 which are adapted to be slidably engaged with the 30 guide channels 6 on the ends of the end pieces 1 and 2 whereby said sides and ends are locked together to form the corners of the coop. On the lower edges of the sides 5 are formed laterally and outwardly projecting locking flanges 20 to which are secured the flanged edges of the bottom hereinafter described.

The bottom 3 has its side edges bent downwardly and laterally to form offset right 40 angular locking flanges 21. The ends of the bottom are bent downwardly to form supporting flanges 22, said flanges being bent outwardly and upwardly to form channels 23 with which are engaged the lower edges 45 of the front and rear end pieces of the coop. With the channel thus formed on the front end of the bottom is also engaged the lower end of the door 12 when the latter is in a closed or partly closed position. By thus 50 engaging the lower end of the door with said channel said lower end of the door will be slidably secured and prevented from being swung upwardly to an open position, until lifted bodily to a sufficient height to 55 disengage the lower edge thereof from the channel. When thus constructed the bottom is adapted to be inserted between the sides and ends of the coop and by means of the offset flanges 21 and 22 will be elevated in 60 the coop above the surface of the ground. When thus arranged the right angularly laterally projecting portions of the side flanges 21 will fit under and support the flanges 20 on the lower edges of the sides 5 65 when sides and bottom may be secured to-

gether by locking members 23, said members 23 comprising metal strips bent inwardly along one edge to form a channel 24 adapted to be slipped over the flanges 20 and 21 of the side and bottom. The opposite edges of the 70 strips are bent at right angles to form stop flanges 25 which when the channels 24 are engaged with the flanges 20 and 21 will closely engage or fit against the inner sides of the vertical portions of the flanges 21 on the 75 side edges of the bottom as clearly shown in Fig. 3 of the drawings, and the bottom 3 will rest on the upper edges thereof. When the locking members 23 are thus engaged with the flanges on the adjacent 80 edges of the sides, and the bottom, these parts will be securely fastened together and the flanges 22 on the ends of the bottom will securely hold the ends of the coop in place. By thus arranging the parts it will be seen 85 that the entire coop will be firmly secured together and cannot be separated until the locking members 23 are first removed after which the various other parts of the coop may be readily disassembled and nested together to form a small package.

To the curved top piece 4 of the coop is preferably secured a suitable handle 26 whereby the coop may be readily lifted and moved from place to place.

From the foregoing description taken in connection with the accompanying drawings the construction and operation of the invention will be readily understood without requiring a more extended explanation.

Various changes in the form, proportion and the minor details of construction may be resorted to without departing from the principle or sacrificing any of the advantages of the invention as defined in the appended claims.

Having thus described my invention, what I claim is:

1. A knock-down chicken coop comprising a bottom piece having its side edges bent downwardly to form vertical supporting flanges to raise the bottom and horizontal flanges extending outwardly from said supporting flanges, side pieces provided with outwardly projecting horizontal flanges, said side pieces and flanges being seated in the outer angle of the vertical and horizontal flanges of the bottom, and a locking member slidable upon and embracing the joint between the bottom and each side comprising a horizontal box inclosing the two horizontal flanges and a vertical flange inside the vertical flange of the bottom reaching to and serving to support the bottom.

2. A knock-down chicken coop comprising a bottom provided on its ends with flanges, extending downwardly and then upwardly to form supports for the bottom and channels outside of said supports, ends

seated in said channels, one of the ends having a doorway, a horizontal track bar secured to and spaced away from the front face of the end piece above the doorway and 5 extending beyond the sides thereof, and a door provided with a horizontal, vertically elongated loop embracing said track bar and 10 slide laterally and vertically thereon, the bottom of the door when closed or laterally 15 opened, resting in the channel of the bottom flange.

3. A knock-down chicken coop comprising a bottom provided on its ends with flanges, extending downwardly and then upwardly to form supports for the bottom and channels outside of said supports, ends seated in said channels, one of the ends having a doorway, and a door mounted to swing outward, move vertically and slide 20 laterally before said doorway, the lower edge of the door resting when closed in the channel between the flanges of the bottom.

4. A knock down chicken coop comprising front and rear end pieces, combined top and

side pieces, and a raised bottom piece adapted to be inserted into said side and end pieces, said front end piece having formed therein a door opening, a slidably and hingedly connected door adapted to open and close said opening, said door having 25 formed on its upper edge an elongated transversely disposed guide loop, a track bar secured to the front end of the coop and adapted to receive the looped upper end of the door whereby the latter is slidably and 30 pivotally supported at its upper end and may be slipped laterally to a partly open position whereby the door will be supported when swung upwardly to an open position, and means to hold the lower edge of the door 35 in its closed and partly open positions.

In testimony whereof I have hereunto set my hand in presence of two subscribing witnesses.

IRWIN DAVIS.
